(57) **CLAIM**

The ornamental design for compact sensor CII, as shown and described.

DESCRIPTION

FIG. 1 is a perspective view of the compact sensor CII according to the present invention;

FIG. 2 is a right-side view of the compact sensor CII according to the present invention;

FIG. 3 is a left-side view of the compact sensor CII according to the present invention;

FIG. 4 is another side view of the compact sensor CII according to the present invention;

FIG. 5 is yet another side view of the compact sensor CII according to the present invention;

FIG. 6 is a top view of the compact sensor CII according to the present invention; and,

FIG. 7 is a bottom view of the compact sensor CII according to the present invention.

1 Claim, 7 Drawing Sheets
